UNITED STATES PATENT OFFICE.

HERBERT F. PATTON, OF CLEVELAND, OHIO.

PROJECTING APPARATUS.

1,075,789.

Specification of Letters Patent.

Patented Oct. 14, 1913.

Application filed July 27, 1912. Serial No. 711,810.

To all whom it may concern:

Be it known that I, HERBERT F. PATTON, a citizen of the United States, and a resident of Cleveland, county of Cuyahoga, and State of Ohio, have invented a new and useful Improvement in Projecting Apparatus, of which the following is a specification, the principle of the invention being herein explained and the best mode in which I have contemplated applying that principle, so as to distinguish it from other inventions.

The present invention relates generally to projecting apparatus.

There is, at present, on the market a slide of a certain size adapted for use with projecting lanterns, and this slide may really be termed a standard slide.

Among the objects of the present invention is the provision of a projecting lantern with which may be used the standard slides referred to, but which also is adapted to receive slides which are about one quarter the size of the standard slides and which may be manufactured and sold for very much less than the standard slide. Despite the economy which a user may practice by utilizing the smaller slides, the lantern will project an image onto a screen of the same size that will be projected from the standard slides.

The invention also provides a particular slide for use with the lantern.

To the accomplishment of the foregoing and related objects, said invention, then, consists of the means hereinafter fully described and particularly pointed out in the claims.

The annexed drawings and the following description set forth in detail certain mechanism embodying the invention, such disclosed means constituting, however, but one of the various mechanical forms in which the principle of the invention may be used.

In said annexed drawings:—Fig. 1 is a vertical section of a lantern embodying the invention, shown as adapted for use with the smaller slide; Fig. 2 is a section on the line A—A in Fig. 1; Fig. 3 is a broken vertical section, showing the lantern adapted for use with the standard or larger slide; Fig. 4 is a section on the line B—B in Fig. 3, and Figs. 5 and 6 illustrate elements which together form the peculiar smaller slide for use with the lantern.

The lantern comprises a suitable support 1, preferably provided with clamp members

2 adapted to hold an illuminator 3, such as an electric incandescent lamp. A hood 4 is mounted on the support and is adapted to inclose the illuminator, the hood 4 carrying a reflector 5 disposed behind the illuminator and being formed with an air chamber 6 and a vent 7. A light conduit or tube opens from the hood and is conveniently formed with a portion 8 extending from a vertical plate of the support rearwardly into the hood, and an outer portion 9 secured to the vertical plate by a plurality of pins 12, although the conduit may be formed, of course, as a continuous tube. Two plano-convex lenses 10 are mounted in the inner end of the conduit and together constitute a condenser for the rays of light directed forwardly from the illuminator. Forwardly of the condenser the light conduit is formed with a transverse opening 11 which is of such size as to receive a carrier in which has been placed a lantern slide of the larger or standard size. Forwardly of the opening 11 is a second transverse opening adapted to receive the carrier 21 in which has been placed the smaller slide which is preferably of the construction hereinafter described. The opening adapted to receive the smaller slide is shown as formed between the vertical plate of the support and the rear plate of the outer portion 9 of the light conduit, and the pins 12 which support the outer portion of the conduit form the upper and lower guides for the carrier 21. It is obvious, however, that this opening and the guides for the carrier may be formed in other ways as, for instance, like the opening 11. In the outer portion 9 of the light conduit is slidably fitted a tube 13 which carries an objective 14 adapted to project on a screen an image from a standard slide mounted in the holder formed by the opening 11. The objective 14 is shown as a plano-convex lens and it may be conveniently mounted in the tube 13 by securing it against a ring 15 fixed in the tube by means of a cap 16 threaded on the tube. Inwardly from the objective 14 is an annular diaphragm 17. As shown in Fig. 1 a second tube 18 is slidably and removably fitted in the inner end of the tube 13 and in it is mounted a second objective 19 conveniently secured in the tube against a shoulder 22 by a ring 20, the movement of the second tube forwardly in the first tube being limited by a ring 21 secured in the first tube.

2
In Fig. 3 it will be noted that the second tube 18 is not included within the tube 13. Furthermore, in this figure the carrier 21 with the smaller slide is omitted, and in its place is shown a carrier 22 in the holder formed by the opening 11, and the carrier holds in place a larger or standard slide formed by placing in the carrier a cover glass 23 and a glass 24 which bears the representation whose image it is desired to project.

In operation, if the user of the lantern has on hand the standard slide and desires to project its image, he will leave out the tube 18 with its objective 19 and will use merely the tube 13 with its objective 14 and he will place the standard slide in position in the holder formed by the opening 11. The objective is designed to project the image from the standard slide, the proper focus being gained by longitudinally adjusting the tube 13 in the outer portion 9 of the conduit. If the user, however, desires to provide himself with the smaller slides at a very considerable saving compared with the cost of the larger or standard slide, he may quickly adapt the lantern for use with the smaller slide. He first removes the tube 13 from the conduit portion 9 and inserts in the tube the second tube 18 with its objective 19, the objectives 14 and 19 both being plano-convex with their convex surfaces facing toward each other. The tube 18, carrying the tube 18 is then longitudinally adjusted in the conduit portion 9 and the smaller slide having been inserted in the holder formed by the pins 12, or otherwise, the image will be projected on the screen by the combined effect of the two objectives.

The objectives are so designed that they will change the focal length corresponding with the difference in size of the larger and smaller slides. As shown in the drawings, the representations provided on the smaller slide are substantially one quarter the size of the representations provided on the larger slide, and the objectives are so designed that when used together the focal length is half of that when the objective 14 is used alone, so that if the lantern is placed at a given distance from the screen the image projected from the larger slide by the objective 14, and the image projected from the smaller slide by the two objectives together will be the same in size, substantially.

The invention also provides a smaller and more economically manufactured and hence lower priced slide for use with the double objective, and attention is directed to Figs. 5 and 6. The invention provides a frame 33, preferably rectangular in shape which is provided with two similar openings 34 and with a flange 25 formed at the edge of the frame. A plain glass 26 is designed to receive on its opposite sides mats 27 provided

with openings 28 adapted, in the assembled condition of parts, to register with the openings 34 in the frame. In the assembled condition of the parts, it is contemplated that the glass plate 26 with its mats 27 will be 70 fixedly secured in the frame 33.

The invention provides also a transparent plate 29 formed on one side with two film representations 30 designed in the assembled condition of parts to register with the openings 28 and 34. The two representations 30 are, in practice, different pictorial views, and the film surface is coated with some protective medium such as varnish. There will be provided for the user a variety of plates 29 with a variety of representations on them, and the user having selected the desired plate 29 from his supply, places it in the frame 33 with the film side facing inwardly against the cover glass secured in the frame 33 and then places the assembled parts in the carrier 21 which is then inserted in the holder formed either by the pins 12, or otherwise.

It will be noted that in the slide described 90 there is provided a comparatively small plate formed with two pictures or other representations, and that these may be more or less freely handled because the film surface is covered with a protective medium. The 95 frame has within it a cover glass, and this frame receives any of the smaller plates which the user desires to use so that only one cover glass is needed and with it can be used any one of a great number of the 100 smaller plates 29. In the standard slide, such as is shown in Fig. 3, each separate slide is formed by a cover glass 23 which is fixedly secured to a film plate 24, so that a 105 separate cover glass is provided for each plate.

The invention therefore provides a projecting lantern adapted to project images from either of two slides of different size by using alternatively a single objective, or that 110 single objective in conjunction with a second removable objective, and the invention also provides an improved slide more economically manufactured than the standard slide, for use with the lantern.

115 Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In apparatus of the class described, the 125 combination of means for holding a slide provided with a representation; an objective adapted to project the representation; means for holding another slide provided with a representation smaller than the first-named 130

- representation; and a second objective removably secured relatively to the first objective, the two objectives together being adapted to project the smaller representation.
2. In apparatus of the class described, the combination of a support; means supported by the support for holding a slide provided with a representation; an objective supported by the support and adapted to project the representation; means supported by the support for holding another slide provided with a representation smaller than the first-named representation; and a second objective removably supported by the support and adapted with the first objective, to project the smaller representation.
3. In apparatus of the class described, the combination of a support; means supported by the support for holding a slide provided with a representation; a tube removably secured to the support; an objective mounted in the tube and adapted to project the representation; means supported by the support for holding another slide provided with a representation smaller than the first-named representation; a second tube removably fitted in the first tube; and a second objective mounted in the second tube and adapted, with the first objective, to project the smaller representation.
4. In apparatus of the class described, the combination of a support; a light conduit mounted on the support; a holder carried by the conduit for holding a slide provided with a representation; a tube removably fitted in the outer portion of the conduit; an objective mounted in the tube and adapted to project the representation; a second holder carried by the conduit forwardly of the first holder and adapted to hold a slide provided with a representation smaller than the first-named representation; a second tube removably fitted in the first tube between the objective and the second holder; and a second objective mounted in the second tube and adapted, with the first objective, to project the smaller representation.
5. In apparatus of the class described, the combination of a support; means secured thereto for holding an illuminator; a hood; a light conduit opening through the hood; a condenser mounted in the conduit; a transverse opening through the conduit forwardly of the condenser for holding a slide provided with a representation; a tube removably fitted in the outer portion of the conduit; an objective mounted in the tube and adapted to project the representation; a second transverse opening through the conduit intermediate the first opening and the outer conduit portion and adapted to hold a slide provided with a representation smaller than the first-named representation; a second tube removably fitted in the first tube rearwardly of the objective; and a second objective mounted in the second tube and adapted, with the first objective, to project the smaller representation.
6. In apparatus of the class described, the combination of a support; means secured thereto for holding an illuminator; a hood; a light conduit opening through the hood; a condenser mounted in the conduit; a transverse opening through the conduit forwardly of the condenser for holding a slide provided with a representation; a tube removably fitted in the outer portion of the conduit; an objective mounted substantially at the outer end of the tube and adapted to project the representation; an annular diaphragm in the tube rearwardly of the objective; a second transverse opening through the conduit intermediate the first opening and the outer conduit portion and adapted to hold a slide provided with a representation smaller than the first-named representation; a second tube removably fitted in the first tube rearwardly of the diaphragm; and a second objective mounted substantially at the outer end of the second tube and adapted, with the first objective, to project the smaller representation.

Signed by me this 25th day of July, 1912.
HERBERT F. PATTON.
